UNITED STATES PATENT OFFICE.

JOHN BEECHER CROSBY, OF BONSHAW, PRINCE EDWARD ISLAND, CANADA.

CARRIAGE-BRAKE.

SPECIFICATION forming part of Letters Patent No. 392,910, dated November 13, 1888.

Application filed November 1, 1887. Serial No. 253,974. (No model.)

To all whom it may concern:

Be it known that I, JOHN BEECHER CROSBY, of Bonshaw, in Prince Edward Island, Dominion of Canada, have invented a certain new and useful Improvement in Carriage-Brakes, of which the following is a description sufficiently full, clear, and exact to enable any person skilled in the art or science to which said invention appertains to make and use the same, reference being had to the accompanying drawings, forming part of this specification, in which—

Figure 1 is a top plan view showing my improved brake in position for use; Fig. 2, a side elevation of the same with the whiffletrees removed; and Figs. 3, 4, and 5, enlarged views showing details of construction.

Like letters and figures of reference indicate corresponding parts in the different figures of the drawings.

My invention relates to that class of carriage-brakes which are automatic in their action or operated by the horses drawing the carriage, in contradistinction to those which are operated by the driver; and it consists in a novel construction and arrangement of parts, as hereinafter more fully set forth and claimed, the object being to produce a simpler, cheaper, and more effective device of this character than is now in ordinary use.

The nature and operation of the improvement will be readily understood by all conversant with such matters from the following explanation.

35 In the drawings, A represents the forward axle, B the forward wheels, and C the pole, of a carriage, these parts being of the ordinary form and construction, excepting as herein-after specified.

40 A horizontally-arranged doubletree, D, is disposed on the pole C in front of the wheels B, said tree being fitted to slide longitudinally on the pole by means of a bolt, m, which passes vertically through an elongated slot, t, in the 45 pole and secured by a nut, b. The doubletree D is provided with whiffletrees E, to which the traces of the harness are attached in the usual manner. A rigid bar, F, is disposed on the pole C, said bar being fitted to slide in 50 bearings v on said pole, and having its rear or inner end secured centrally to the doubletree

D, as shown at w. The outer end of the bar F is provided with a sheave or truck, d, over which a chain, f, passes, one end of said chain being secured to a clip, g, on the end of the 55 pole, and the other to the hanger h of the yoke G, which is fitted to slide on said pole, and provided with hooks x for the breech-straps of the harness.

Secured to each end of the doubletree D 60 there are two plates, H, provided with corresponding forwardly-curved slots, r, and disposed between each pair of said plates there is a brake-shoe, J, adapted to engage the wheel B, and concaved on its face to correspond with 65 the peripheral contour of the wheel. A horizontally-arranged bolt, i, is secured to each of said shoes, the ends of said bolts projecting into the curved slots r in the plates H and constituting trunnions on which the shoes are 70 pivoted, thereby adapting said shoes to rock and also slide diagonally upward between said plates.

In the use of my improvement the traces or lugs of the harness are secured to the hooks z 75 on the whiffletrees E and the breeching-straps or "holdbacks" to the hooks x on the yoke G. The horses being harnessed to the carriage, as described, and the carriage descending a hill, if now it is desired to apply the brake, the 80 horses are so reined as to cause the breeching-straps to slide the yoke G toward the wheels B, thereby pulling on the chain f, forcing the bar F and doubletree toward the axle A, and causing the shoes J to press against the wheels 85 B and apply the brake to the carriage in a manner which will be readily understood by all conversant with such matters without further explanation.

In applying the brake it will be obvious that 90 as long as the carriage continues to advance or the wheels to revolve in the direction of their arrow the bolts i will remain in the lower portion of the slots r and the shoes J will "wedge" between the plates H and the 95 wheels B, thereby effectually "braking" the carriage; but when the horses are backed sufficiently to cause the wheels to revolve in the opposite direction the bolts i will slide upward in the slots r and the shoes J be disengaged from the wheels B, thereby permitting 100 the carriage to be backed without interference

from the brake. It will thus be seen that the brake is automatic in its operations, being actuated by the horses independently of the driver, excepting as guided by him in the ordinary course of driving them.

Having thus explained my invention, what I claim is—

1. In a carriage-brake of the character described, the combination of the following instrumentalities, to wit: an axle, wheels mounted on said axle, a pole, a doubletree fitted to slide on said pole adjacent to said wheels and provided with whiffletrees, slotted plates mounted on the ends of said doubletree, brake-shoes fitted to slide in said slotted plates and adapted to engage said wheels, a yoke fitted to slide on said pole near its forward end and provided with hooks for the breeching-straps, and a bar fitted to slide on said pole, said bar being connected with said yoke and said doubletree, substantially as set forth.
2. The improved carriage-brake herein de-

scribed, the same consisting, essentially, of the pole C, provided with the slot t, the sliding doubletree D, provided with the bolt m and nut b, the whiffletrees E, provided with the hooks z, the plates H, provided with the curved slots r and mounted on said doubletree, the shoes J, provided with the bolts i 25 and fitted to slide between said plates, the yoke G, having the hooks x and fitted to slide on the pole C, the bar F, connected with the doubletree and fitted to slide on said pole, said bar being provided with the sheave d, and the 30 chain f, passing over said sheave and connected at one end to said bar and at the other to said pole, all being constructed, combined, and arranged to operate substantially as described.

JOHN BEECHER CROSBY.
